ATTORNEY

UNITED STATES PATENT OFFICE.

CHARLES B. DYGERT, OF ILION, NEW YORK, ASSIGNOR, BY MESNE ASSIGNMENTS, TO REMINGTON ARMS COMPANY, INC., OF NEW YORK, N. Y., A CORPORATION OF DELAWARE.

FIREARM.

1,381,291.

Specification of Letters Patent. Patented June 14, 1921.

Application filed January 10, 1920. Serial No. 350,561.

To all whom it may concern:

Be it known that I, CHARLES B. DYGERT, a citizen of the United States, residing at Ilion, in the county of Herkimer and State 5 of New York, have invented certain new and useful Improvements in Firearms, of which the following is a specification.

This invention relates to that class of firearms in which the barrel is without longitudinal movement relative to the frame, but is detachably united thereto.

While my present improvements are applicable to firearms of all kinds they are especially applicable to that class of small- 15 arms among others, which are commonly designated as auto-loading pistols, and which usually comprise three principal members, including a frame; a bolt-carrier (or "breech-slide") slidably mounted on the 20 frame; and a non-reciprocating barrel slidably supported at its forward end in the bolt-carrying slide, and at its rear end detachably connected to the frame.

My present invention comprises an improvement on the invention shown and claimed in the application of John D. Pedersen, S. N. 204,149 (renewed as S. N. 314,426) which relates to an improved interlock connection for detachably uniting 25 the barrel to the frame, comprising a transverse bar or "cross-bar" which directly and releasably unites the barrel to the frame.

One of the principal objects of this invention is to provide such a cross-bar which 35 shall be continually subjected to frictional control by a force derived from the breech-slide-actuating spring and transmitted to said cross-bar through the barrel, breech-slide and frame.

More specifically it is an object to provide 40 clearance between the barrel and frame and otherwise so to arrange the various coacting parts that the barrel and frame uniting cross-bar continually supports the reaction 45 of the breech-slide-actuating spring and therefore is frictionally held in place thereby against ready inadvertent displacement.

These and other features, capabilities and 50 advantages of the invention will appear from the subjoined detail description of one embodiment and a modification thereof, illustrated in the accompanying drawings, in which

Figure 1 is a side elevation, partly in sec-

tion, of an automatic pistol embodying my 55 present invention;

Fig. 2 is a sectional view on the line 2—2 of Fig. 1, and

Fig. 3 is a partial view similar to Fig. 1, showing a slight modification. 60

In said drawings the numeral 4 designates generally the frame of an auto-loading pistol of any type to which my invention is applicable. This frame member may in practice be of any suitable design and proportions, the design shown being substantially that illustrated in application, S. N. 42,774, filed July 30, 1915, by John D. Pedersen, which may be considered typical of various other such frames well known in this art. 70 The frame is formed with a handle 5 of usual or suitable form.

The numeral 6 designates the breech-slide, shown slidably mounted on the frame 4 by the usual interengaging rib and groove joint 75 7. The breech-slide 6 carries the breech block 8 which may be rigidly connected to the slide or be relatively movable as in said Pedersen application S. N. 42,774. The numeral 9 designates the trigger which may 80 be of usual form and serves to release the firing mechanism (not shown).

The barrel 10 is substantially inclosed within the breech-slide chamber, the forward end being slidably supported in the bearing 85 14 which may be formed as a bushing secured to the breech-slide. The bushing shown herein is the subject matter of an application filed by C. C. Loomis, December 4, 1919, S. N. 342,397. Surrounding the barrel 90 and resting against said bearing is the breech-slide-actuating spring 13, the rear end of which bears against a shoulder on the barrel or against a ring 15 which may be formed with a sleeve extension 15' surrounding the first few coils of the spring and concealing them from view through the ejection port 16.

The rear end of the barrel and the frame 100 are formed with cooperating interlock portions as a lug 11 on the barrel fitting in a recess in the frame. The barrel is held in fixed relation to the frame, both vertically and horizontally, by means of a cross-bar 12 located in cross-bar seats such as apertures 105 4' in the frame and 10' in a portion of the barrel or an extension thereof as the lug 11. This cross-bar may be of circular cross sec-

tion as in Figs. 1 and 2 or of any other cross section, as square, as shown at 12' in Fig. 3. A clearance, as 17, is provided between the barrel and frame so as to permit of a slight 5 rearward movement of the barrel from normal when the cross-bar is removed. Therefore, when the parts are in assembled position the reaction of the breech-slide-actuating spring is always supported by the cross-bar 12 except possibly during the very short 10 interval when the bullet is passing from the barrel at which time the cross-bar restrains forward movement of the barrel. The cross-bar 12 is therefore at all times under a frictional control and is thereby held against 15 inadvertent removal.

Another important feature of my present invention is that the hole 10' is entirely in the barrel and the hole 4' is entirely in the 20 frame. For this reason, these holes are more easily formed and more accurately located than would be the case if they extended to the edge of the frame or barrel. For this reason, also, the barrel is fixedly secured to 25 the frame against not only longitudinal but also against vertical movement, although the interlocking portions of the barrel and frame are not undercut or dovetailed as has been proposed heretofore. This results in a 30 cheaper construction, without depending upon the breech-slide 6 to limit the upward movement of the barrel. This rigid construction provides a more accurately shooting arm by preventing any vertical movement 35 of the barrel and results in a more reliable arm in that the primer is always properly aligned with the firing pin point.

It is well-known that in manufacturing the parts of firearms of the general class 40 herein represented, it has become customary to make cylindrical openings or holes at certain convenient points in the part or parts from which these parts may be located by means of suitable plugs which are a part of 45 the fixtures by means of which the successive finishing operations are performed in the manufacture of the firearm. Accordingly in my present improvements, especially when the barrel-and-frame-uniting 50 pin, as 12, is a cylindrical one, the bore at 4' in the frame and the bore at 10' in the barrel, may be utilized as gaging points from which to locate other cuts, and the making of other 55 specific dimensions, on the rearward end of the barrel and with relation to working faces on the frame and within the slide 6, so that these several parts when the mechanism is assembled, shall have an accurate relationship thus indirectly obtained. Thus, as re- 60 gards the rear face of the barrel and the corresponding forward face of the frame, these may now be made with a low degree of accuracy providing a free space at 17 and also thereby avoiding the necessity for a highly 65 precisionized locating of the said barrel and

frame surfaces. By these means the machining operations in the production of the arm may be materially facilitated and cheapened while producing the perfect result as regards the assembling and functioning of the mechanism. 70

Other devices may be employed to assist in holding the cross-bar in place as for example the means shown in the J. D. Pedersen application S. N. 204,149 referred to 75 above, my present invention having been found of great utility in holding the cross-bar in place during the time the recess in the slide is passing the end of the cross-bar in the device of said application. 80

The cross-bar being merely frictionally held may be readily withdrawn for disassembling the arm which in the form shown may be done by moving the breech-slide and barrel forwardly off the frame. 85

What I regard as my invention and desire to secure by Letters Patent of the United States is:—

1. In a firearm, the combination with a frame and a barrel, of a slide supported for 90 reciprocating movements forwardly and rearwardly on the frame, said frame and barrel each having near the rearward end of the barrel interlock portions provided transversely with alined cross-bar seats, a 95 barrel-and-frame uniting cross-bar disposed in said alined seats, and a slide-actuating spring bearing against said slide and against said barrel, the parts being so fitted that the reaction of said spring is supported entirely 100 by said cross-bar, whereby it is frictionally held in place in said cross-bar seats.

2. In a firearm, the combination with a frame, of a chambered slide supported on the frame and having depending side-walls slidably engaging the frame, a barrel in the chamber of the slide and having an enlarged rearward end, a slide-actuating spring reacting against said enlarged barrel-end, said enlarged barrel-end and the frame 110 having interlock portions provided with alined cross-bar seats, and a cross-bar disposed in said alined seats of the frame and barrel; said parts being so fitted that the reaction of said spring is supported by said 115 cross-bar, whereby it is frictionally held in place in said cross-bar seats.

3. In a firearm, the combination with a frame, of a chambered slide supported on the frame and having depending side-walls slidably engaging the frame, a barrel in the chamber of the slide and having an enlarged rearward end, a slide-actuating spring reacting against said enlarged barrel-end, said 120 enlarged barrel-end and the frame having interlock portions provided with alined cross-bar seats, and a cross-bar disposed in said alined seats of the frame and barrel; the parts being so fitted that the barrel is restrained against longitudinal movement 125 130

by said cross-bar, which therefore supports the reaction of said spring and is frictionally held in place thereby.

4. In a firearm, the combination with a frame and with a barrel, of a slide supported for reciprocating movements forwardly and rearwardly on the frame, said frame and barrel each having near the rearward end of the barrel interlock portions provided transversely with alined cross-bar seats, a barrel-and-frame uniting cross-bar disposed in said alined seats, and a slide actuating spring bearing against said slide and barrel, the said parts being so fitted that forward and rearward movement of the barrel is restrained only by said cross-bar, whereby said cross-bar supports the reaction of said spring and is frictionally held in place thereby.

5. In a firearm, the combination with a frame, of a chambered slide supported on the frame and having depending side-walls slidably engaging the frame, a barrel in the chamber of the slide and having an enlarged rearward end, a slide-actuating spring reacting against said enlarged barrel-end, said enlarged barrel-end and the frame having interlock portions provided with alined cross-bar seats, and a cross-bar disposed in said alined seats of the frame and barrel; the said parts being so fitted that longitudinal movement of the barrel is restrained only by said cross-bar, whereby said cross-bar supports the reaction of said spring and is frictionally held in place thereby. 30

CHARLES B. DYGERT.
